PUMP CONTAINER

Thomas W. Winstead, Baltimore, Md.

Application March 25, 1946, Serial No. 656,948

3 Claims. (Cl. 230—32)

1

My invention relates to a pump container adapted for carrying and inflating articles such as bathing floats, air mattresses, and similar articles.

When articles of any considerable size of the inflatable type, such as bathing floats, are manufactured it is particularly necessary to have a separate pump arrangement to inflate the articles. They are too large to comfortably inflate by means of the mouth, and the use of containers of compressed gas is not desirable. Where reference is made herein to bathing floats it is to be understood that the inventions are applicable to air mattresses, and in fact to all articles of the general class which includes these two specifically named articles.

It is to meet the need of transporting and inflating articles, such as bathing floats, that this pump container has been designed. It is to be noted that the inside of the compartment in which the article to be inflated is carried is unobstructed. The construction is simple, compact and useful.

The article in general comprises two telescopic members, which may be of cylindrical cross section, which are unobstructed in their interior, and within which the article to be carried such as a bathing float is carried. One end of one of the telescopic members carries a check valve, and the other end of the other telescopic member is provided with means to permit it to be attached to the intake valve of the article to be inflated.

With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying drawings means for carrying the same into practical effect without limiting the improvements in their useful applications to the particular constructions, which, for the purpose of explanation have been made the subject of illustration.

In the drawings:

Figure 1 is a perspective view showing my pump container with parts cut away to show how the article to be inflated is carried within the interior of the container.

Figure 2 is a perspective view showing the telescopic parts separately illustrated with the article

2

to be inflated in one of the telescopic members.

Figure 3 is a perspective view showing the telescopic parts separately illustrated with the article to be inflated in one of the telescopic members.

Figure 4 is a perspective view showing the bathing float in the process of being inflated and illustrating the operation of the pump container as a pump.

10 Figure 4 is a view in side elevation of the pump container.

Figure 5 is a view taken along the line 5—5 of Figure 4 looking in the direction of the arrows.

Figure 6 is a sectional view taken along the line 6—6 of Figure 5 looking in the direction of the arrows.

Figure 7 is a sectional view taken along the line 7—7 of Figure 5 looking in the direction of the arrows.

20 Figure 8 is a view in side elevation of a modified form of my pump container.

Figure 9 is a view taken along the line 9—9 of Figure 8 looking in the direction of the arrows.

Figure 10 is a sectional view taken along the line 10—10 of Figure 9 looking in the direction of the arrows.

Figure 11 is a sectional view taken along the line 11—11 of Figure 9 looking in the direction of the arrows.

30 My pump container comprises an elongated cylindrical container 1 formed of two telescopic members 2 and 3 which may be formed of spirally wound paper or any other desirable construction. The member 2 is adapted to fit over the member 3. The member 3 has a stop collar 4 formed thereon which limits the sliding movement of the member 3 and also acts as a reinforcement for the end of the telescopic member 3.

40 The telescopic member 2 has a metallic cap 5 seamed to the tube 2. The cap 5 is provided with an aperture 6 which is struck out of the blank of the cap and which is provided with an inwardly projecting lip 7. Over the lip 7 is adapted to be stretched an elastic strip which

45 may be of a vinyl ester, or some other elastic material 8. This strip can be seamed to the tube in an assembly operation. The construction here just described forms a check valve. The flexible strip 8 contacts inwardly projecting lip 7 of the aperture 6 and makes a reasonably air-tight fit at the contact point of the annular projecting lip with the flexible strip 8 thus insuring a minimum of escape of air at this intake valve after the telescopic members have been

50 caused to telescope one within the other to com-

press the air within the unobstructed interior 9 of the container 1. This unobstructed interior permits the article, such as a bathing float, to be rolled and carried easily without danger of injury in a compact roll within the container 1.

The telescopic member 3, as has been described, is provided with an annular stop collar 4 which acts as a reinforcing member. This annular stop collar 4 limits the telescopic movement of members 2 and 3 in the compressing cycle of the pump 10 container.

The telescopic member 3 has seamed into one of its ends a cap 11 which may be of metal or any other suitable material. This cap 11 is provided with an aperture 12 which is formed with an inwardly projecting lip 13 similar in construction to inwardly projecting lip 7 at the aperture 6 of the end cap 5 of the telescopic member 2.

This aperture 12 is adapted to fit over a valve 14 (see Figure 3) formed in a float 15 which is carried in the interior of the telescopic container but which is shown in Figure 3 removed from the container and being inflated. The valve 14 is a one way valve and is the intake valve for the float 15.

In operation the float 15 or other article to be inflated is removed from the cylindrical container 1. The aperture 12 with its lip 13 acting as a guide is fitted over the intake valve 14 of the article 15. The telescopic members are given relative movement back and forth. The air is sucked into the interior 9 of the cylindrical container 1 through the check valve mechanism just described and is discharged through the aperture 12 through the valve 14 into the float 15 or other article to be inflated.

In Figures 8 and 9 a modification is shown in which the stop collar 4 has been eliminated. This decreases the weight of the container and simplifies the construction. The telescopic member 3 then contacts the cap 5 of the telescopic member 2 which limits its movement. There is no stop collar to assist in limiting this movement as in other forms shown, and the construction is somewhat more fragile than the form illustrated in Figures 1 to 7 inclusive. However, weight is saved and manufacturing costs are reduced, and under certain conditions this is desirable.

Because the interior of the pump container is substantially unobstructed the pump container can be packed and unpacked without danger of injury to the article carried. Moreover, because the construction is simple and positive in operation there is small danger of rendering the pump container inoperative in its function of inflating the article which is adapted to be carried and inflated by the construction just described. The simple and sturdy construction at the openings provided in the ends insures the check valve construction which is positive in operation with small 60

leakage of air by reason of the limited contact area between the inwardly projecting lip at the aperture and the flexible strip stretched across the lip. Moreover the inwardly projecting lip at the other end acts as a guide to enable the aperture in that end to be fitted readily over the intake valve of the article to be inflated.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

1. A container and pump element comprising a pair of telescopic parts having a close sliding fit 20 and forming a closed compartment, the inner wall of the inner part forming an unobstructed surface from one end to the other of the parts when in completely telescoped position, an air intake valve mounted on one of said parts, an 25 inflatable article in said compartment including a valve secured thereto, and an air outlet port complementary to said article valve formed in the other of said parts whereby relative motion between said telescoping parts will inflate the 30 article when said article valve and said port are in complementing relationship.

2. A device as recited in claim 1 in which the inner of said parts is longer than the outer part to project substantially therefrom in fully telescoped condition of the parts to provide hand 35 holds on the two parts for the said telescoping pumping movement.

3. A device as recited in claim 2 in which the outside dimensions of the projected end of the 40 inner part are enlarged to equal the outside dimensions of the outer part to provide a collar to limit the inward telescoped position of the inner part in the outer part and provide a smooth outer surface for the device when the two parts 45 are in fully telescoped condition.
